UNITED STATES PATENT OFFICE

2,461,443

PIPE BOWL TURNING MACHINE

Julius L. Rettke and Edmund H. Otto, Washington, Mo., assignors to Missouri Meerschaum Company, Washington, Mo., a corporation of Missouri

Application October 6, 1944, Serial No. 557,509

8 Claims. (Cl. 144—47)

1

The present invention relates generally to a novel machine for turning the bowls of tobacco pipes, particularly, though not exclusively, the bowls of the well-known "corn-cob" variety.

Heretofore, the turning operations in producing corn-cob pipe bowls have been done manually. In other words, the properly conditioned cobs are initially sawn into cylinders of predetermined size, and each cylinder is then hollowed out by a simple boring process, preparatory to placing it upon the spindle of a lathe. Thereupon, only a skilled artisan is able to perform the turning operation by dexterous manipulation of a chisel. Following this manual turning operation, the exterior of the bowl is sanded, also by hand. There are subsequent operations, but these are not within the purview of this invention.

The disadvantages of manual turning as compared to the rhythmic output of the machine illustrated and to be described are numerous. Separate handling, for instance, is at present required to complete the turning and sanding operations manually; whereas, in the use of the invention, such handling is obviated.

Further, regardless of the skill of the artisan, the individual units of a quantity of hand-turned bowls frequently vary in shape, and thus also in weight. Although this has not been found critical, yet the uniformity of the bowls produced by the present machine leaves nothing to be desired.

Again, the manual turning and sanding operations are tedious, and the skill required, particularly to perform the turning, is acquired only after years of diligent application. It should be borne in mind in this connection that the external contour pattern of the bowls is greatly diversified. In using the machine of this invention, a rotary cutter is employed whose blades insure a uniform output, each unit of which is shaped exactly as its predecessor and according to a selected pattern. Should a different bowl configuration be desired, it is only necessary to insert a corresponding set of blades in the cutter.

It is, therefore, an object of this invention to overcome the disadvantages mentioned, and also to provide a machine whose attendant need but place the bored corn-cob cylinder on one of a circular series of spindles or arbors carried by a constantly rotating disc driven at a comparatively slow rate of speed, as will be explained.

A further object of the invention is the provision of means whereby the loading operation just described is the only one required of an attendant. A positive bowl-turning cutter as-

2

sembly is provided. A novel sanding or bowl-exterior smoothing assemblage is incorporated in the machine. Means are provided for automatically removing the ultimate bowl from its supporting spindle, so that the spindle may again receive a raw corn-cob cylinder in its orbit toward the cutter.

Other objects and features of the invention, if not specifically designated, will be apparent from the description to follow, reference being had to the three accompanying sheets of drawings, which portray a preferred structure.

In said drawings:

Fig. 1 is a plan view of the machine;

15 Figs. 2 and 3 are, respectively, a front and a rear elevational view thereof;

Fig. 4 is a fragmentary vertical sectional view taken substantially on line 4—4 in Fig. 1, illustrating the means for rotating a plurality of spindles simultaneously;

Fig. 5 is a fragmentary vertical sectional view on an enlarged scale through the sanding or burnishing assembly, taken substantially on line 5—5 in Fig. 1;

Fig. 6 is a vertical sectional view on an enlarged scale taken on line 6—6 in Fig. 5;

Fig. 7 is a similar view on line 7—7 in Fig. 2, and includes a diagrammatic broken line showing of certain operations;

20 Fig. 8 is an enlarged elevational view partly in section of a portion of the machine. The line 8—8 in Fig. 1 approximately indicates the location of the parts included;

Fig. 9 is a detail view of a structure which 25 cooperates with the rotary cutter;

Fig. 10 is a vertical sectional view taken on line 10—10 in Fig. 9;

Fig. 11 is a fragmentary view partly in section 30 particularly illustrating the mechanism for removing each finished bowl from its supporting arbor. The line 11—11 in Fig. 2, and in Fig. 3, indicates approximately where the view is taken;

Fig. 12 is a sectional view on line 12—12 in Fig. 11;

Fig. 13 portrays a gear provided with a circular series of cams or lobes on one of its faces;

Fig. 14 is a sectional representation of a raw 35 corn-cob cylinder as it appears when fed into the machine; and

Fig. 15 is a similar representation of the finished product as it appears when ejected from the machine.

A horizontally disposed framework generally indicated A is mounted on a suitable base B, 50 which may comprise a pair of standards adapted

to be fastened to a foundation. The standards may be connected by cross members *b* to form a unitary structure, and a number of brace members *a* are provided to support the overhanging portions of the framework *A*, as illustrated. Thus, a rigid foundation is provided, minimizing vibration.

An electric motor *M*, mounted on the framework *A*, has a sheave fixed to each projecting end of its shaft. The first of these sheaves, designated *16*, drives by means of a belt *17* a relatively large pulley *18* whose shaft is mounted in bearings *19* fixed to the frame. Adjacent the pulley *18*, said shaft has a pinion *20* in mesh with a large gear *21* of a speed reduction train which includes pinion *22* in mesh with gear *23* whose shaft carries a pinion *24* in mesh with a final gear *25*.

As a result of this arrangement, the gear *25* rotates relatively slowly, whereas the gear *23* rotates rather rapidly, although at a greatly reduced rate of speed compared to that of the motor *M*.

The gear *25* is fixed to a shaft *26* supported in suitable bearings *27* mounted on the framework, as best seen in Fig. 1. Fixed to said shaft intermediate said bearings is a rotary disc *28* whose rotative speed obviously corresponds to that of gear *25*. A circular series of rotatable spindles or arbors, generally indicated *29*, is carried by said disc. These spindles are adapted to be driven at a high rate of speed whenever the pulleys *30* fixed to each of them is engaged by the belt *31*, in turn driven directly by the second sheave *32* fixed to the shaft of the motor *M*.

The manner in which the spindles *29* are mounted on the disc *28* is clearly illustrated in Fig. 7. Since a high speed of rotation is desirable, anti-friction bearings *33* are provided, and, as shown, end play elimination is obtained by proper positioning of the pulley *30*.

Each spindle *29* is composed of two parts united by a set-screw *34*. The journaled component *35* thereof has an enlarged head portion *36* whose tapered socket *37* receives the correspondingly tapered extremity *38* of the second part *39*, whose configuration is especially important, as will be explained.

The number of spindle assemblies may vary. In the embodiment of the invention illustrated, eight are shown, five of which are driven at a high rate of speed by belt *31*, while the remaining three may idle during each cycle.

Attention is directed to Figs. 2 and 4, for a comprehensive understanding of the manner in which this feature is achieved. It is noted that the upper stretch of belt *31* engages the pulley *30* of that spindle assembly *29* directly above the shaft *26*. Subsequently, it engages the pulleys of four more spindles, but, having now become the lower stretch of said belt, contact with the three remaining spindle pulleys is prevented by means now to be described.

As best seen in Figs. 1 and 2, an arm *40* carrying an idler pulley *41* near its free end is pivotally secured to the frame as at *42*. A support *43*, secured as shown to the frame and to the base, has fixed thereto an angular bracket *44* which slidably supports a vertical rod *45*. The upper end of said rod is connected to arm *40*. The lower end carries an adjustable seat *46* for a coil spring *47* which surrounds the rod and is interposed between said seat and the extension *48* of the bracket through which the rod passes. The idler *41* engages the lower stretch of belt *31*, which, under the action of spring *47*,

47, is thus kept taut at all times and clear of succeeding spindle pulleys *30* as they arrive at the ejection station of the cycle, indicated *x* in Figs. 4 and 11.

The rotary cutter *49* incorporated in the machine is independently driven by a motor *m*, by means of the belt and pulley drive *50*. The shaft *51*, which carries the cutter, is mounted in suitable bearings *52* rigidly fixed to a horizontal base plate *53* to which the motor is also secured. The plate *53* is supported on and horizontally slideable on a base *54*. The entire cutter assembly may thus be positioned toward or away from the center of the machine by means of a threaded adjusting screw arrangement generally indicated *55*. When the proper setting is had, plate *53* is fixed to base *54* by means of a set-screw *56*, or the like. The base *54* may be adjusted transversely of the machine by means of a similar screw arrangement generally indicated *57*, and its position made permanent by means of a set-screw, or the like, *58*.

The cutter *49* is of conventional construction and is adapted for the reception and retention of blades which may have a variety of contoured cutting edges. It is noted, however, that in carrying out the present invention a circular saw *59* is interposed between the body of the cutter and an enlarged portion *60* of the shaft *51*. A similar saw *61* of a smaller diameter is also clamped between the body of the cutter and a nut *62* threaded on the adjacent extremity of said shaft. The manner of removal and replacement of the cutter and the saws is considered obvious.

Particularly in Figs. 8, 9, and 10, an arrangement for cooperation with the cutter is portrayed. The structure includes a channel-shaped up-right member *63* having a base flange *64* which is bolted, or otherwise secured, as at *63* to a portion of bearing *27*. Rigidly secured to the up-right *63* is a laterally extending arm *65* apertured as at *66*. An elongated plate *67* passing through aligned recesses *68* formed in the upright *63* is held in position by means of a bolt *69* and a nut *70*. For reasons to be explained later, this is a loose connection (see Fig. 8). The plate *67* is provided with a countersunk opening *71* adapted to loosely receive the head *72* of a bolt *73* whose opposite end passes through the aperture *66* of arm *65*. A coil spring *74*, surrounding the bolt *73*, is interposed between the plate *67* and the arm *65*. The end of bolt *73* is threaded so that the spring tension may be adjusted by means of a pair of nuts *75*. It should be noted that the diameter of the hole *66* in the arm *65* is considerably larger than that of said bolt.

With particular reference to Figs. 5 and 6, a novel sanding or burnishing arrangement will now be described. Supported by brackets *76*, secured as shown to the cross members *b* of the base, is an arcuately formed plate *77*. Hingedly connected as at *78* to this plate is a similar member *79*, provided with a boss *80* into which is threaded one end of a pin *81* which passes through a hole *82* in the member *77*. A spring *83* surrounds the pin and is interposed between the members *77* and *79*, thereby maintaining them in spaced relation. The end of the pin *81* projecting beyond the hole *82* is also provided with threads for the reception of a nut *84*. By means of this nut, the tension of the spring *83* may be regulated.

The burnishing arrangement proper consists

of three super-imposed layers of material. The lowermost of these, that is, the layer 85 adjacent the plate 79, is of leather. Its upper surface, as best seen in Fig. 6, is slightly concave. The intermediate layer 86 is of soft rubber or similar material, while the top or upper layer 87 is sandpaper. This sandpaper is provided with slits 88 at intervals throughout its length.

The mechanism for ejecting the finished bowl is illustrated, particularly in Figs. 11, 12 and 13. An intermittently reciprocated horizontal bar 89 is slidably supported in brackets 90 secured to an adjacent portion of the base B. A roller 91, mounted in one end of the bar, is alternately in contact with one of a circular series of cam lobes or protuberances 92 formed on the gear 23, and the face of said gear between the cams, as the gear revolves. Such contact is maintained by the interposition of a spiral spring 93 surrounding the bar, between one of the brackets 90 and a pin 94 fixed in one of a number of holes 95 provided therefor in the bar.

The opposite end of the bar terminates in an upstanding extension 89' to which is welded or otherwise secured an arcuately shaped pusher member 95.

Operation

The rotative direction of the principal revolving elements of the machine will be described from the attendant's viewpoint, that is, as seen in Fig. 2. Assuming that both motors are in operation, pulleys 16 and 32 and belts 17 and 31 turn counterclockwise, as do certain of the spindles 29, pulley and belt 50 and the cutter and its associated circular saws. The spindles, directly driven, revolve at a high rate of speed. The cutter and associated circular saws, independently driven by the motor m, rotate at an extremely high velocity. The spindle carrying disc 28 revolves at a moderate rate, due to the speed reduction train of gearing by means of which the motive power from prime mover M is transmitted thereto.

A raw corn-cob cylinder, previously sawn to proper length and provided with a tapered bore, is portrayed in Fig. 14 and designated C. As shown particularly in Figs. 7, 8 and 11, the inner end of each spindle terminates in a tapered head 39' of a size to effect a press-fit in the resilient tapered bore of the cylinder C.

The loading station in the cycle is indicated at Y in Figs. 2 and 4, at which point the spindle there is inert, since its pulley 30 is out of contact with belt 31, as is obvious. Thus it is a simple matter for the attendant to press a cylinder C onto the head 39' of the spindle while the disc 28 is slowly revolving.

The pulley of that spindle shortly comes into contact with the upper stretch of the constantly driven belt 31, whereby said spindle begins to rotate rapidly, and continues to do so as it takes the revolving cylinder C through the cutter mechanism.

The blades of the cutter 49, their edges shaped in accordance with a predetermined pattern, now quickly transform the exterior of the cylinder C into the desired configuration, the circular saws 59 and 61 simultaneously trimming its ends.

In this regard, attention is again directed to Fig. 7, wherein this particular operation is diagrammatically illustrated in broken lines, and wherein the resultant pipe bowl is indicated PB. The original raw cylinder C is outlined by dot and dash lines. Attention is also directed to the

annular channel 39" formed in the periphery of the spindle component 39 to accommodate the end trimming saw 61. Saw 59, of greater diameter, extends at least to or slightly beyond the center line of said cylinder whose adjacent end is unsupported.

In order to steady the leading revolving unsupported end of the bowl PB as it leaves the cutter mechanism (at which stage, incidentally, the saw 59 is completing its work), and, in order to guard against looseness of fit between the head 39' and the bore of the bowl PB at this stage, the structure illustrated in Figs. 8, 9 and 10 is employed.

Thus, as the bowl PB travels beyond the cutter mechanism, its unsupported and now smoothly trimmed end rides for a time along the smooth face of the plate 67. During this interval the bowl is subjected to a gradually increasing pressure by the action of the spring 74. The latter yieldingly forces plate 67 against the end of the bowl and, consequently, reestablishes a press-fit connection between its bore and the spindle head 39' whenever a loose fit develops following the cutting and trimming operations.

Sequentially, the rapidly rotating bowl PB is brought into contact with the burnishing equipment, shown to best advantage in Figs. 5 and 6.

While the turning of an ultimate barrel-shaped bowl is disclosed in the drawings, it has been pointed out heretofore that a variety of external contours may be formed in the machine by the installation of sets of different cutter blades. No change, however, is thereby required in the burnishing equipment, which is so designed as to adapt itself most expeditiously to the various bowl contours subjected to its action.

To this end the member 79 which carries the burnishing equipment is hingedly mounted as described at 78, and is resiliently supported and kept in yielding contact with successive bowls by means of spring 83. Upward movement of the arm 79 is, of course, limited by the adjustable nut 84, the latter also being the means whereby the proper position of member 79 relative to the rotating bowl may be attained.

The bowl-contacting element consists of the sandpaper 67, whose inherent flexibility is increased by the plurality of relatively short slits 88 formed at intervals therein. The layer of soft rubber 86 beneath said sandpaper adds resiliency. The concavity in the upper surface of the leather layer 85 affords a non-rigid backing for the two previously mentioned layers. The composite arrangement obviously is at once inherently adaptable to a great variety of bowl shapes.

Following the sanding operation, the ultimate or finished pipe bowl, shown in Fig. 15 and designated FPB, arrives at the ejection station x, at which point, as should be understood from an earlier description of Figs. 11, 12 and 13, it is discharged from the machine into a suitable receptacle (not shown). The intermittent horizontal reciprocations of the bar 89 obviously follow one another in rapid succession due to the circular series of closely spaced cams 92 on the gear 23, which latter rotates at a speed greater than that of the spindle carrying disc 28. The pusher member 95 is so formed that should one forward reciprocation of the bar 89 fail to dislodge the bowl, the succeeding reciprocation thereof cannot fail to do so.

From the above it should be apparent that the machine attains its objects in a highly efficient manner. While the embodiment illustrated and

described pertains to turning pipe bowls of the "corn-cob" variety, the invention may also be successfully used in the production of wooden bowls of the "hickory" type of pipes.

What is claimed is:

1. A pipe bowl turning machine including a motor, a rotary disc driven thereby through an interposed train of speed reduction gearing, a circular series of rotatable spindles journaled on the disc, means for driving a selected number of said spindles at a high velocity, said means including a belt engageable with pulleys rigid with said spindles, mechanism adapted to maintain said belt taut and simultaneously clear of the pulley of each spindle upon reaching a particular point, rotary cutter mechanism including a pair of spaced circular saws independently driven at a high rate of speed by a second motor, means whereby the cutter mechanism together with its source of power may be properly positioned relative to said spindles, pivotally mounted and resiliently supported burnishing apparatus, means for adjusting its position relative to said spindles, and mechanism activated by cams formed on one gear of said speed reduction gearing adapted to eject the finished bowls from the machine.

2. A pipe bowl turning machine including a base and a horizontally disposed framework supported thereon, a primary motor and a rotary vertically disposed disc whose horizontal shaft is supported in bearings on the framework, speed reduction gearing for transmitting power from said motor to said disc, a circular series of spaced horizontally disposed spindles journaled in bearings near the periphery of the rotary disc, a sheave fixed to one extremity of each spindle, a belt continuously driven at a high rate of speed by said motor engageable with certain of said spindles but not engageable with all of them, a rotary cutter and cylindrical saw unit including a second motor to drive said cutter and saw at a high velocity, a yieldable pressure plate supported on a standard secured to said framework, an adjustable resiliently supported and hingedly mounted bowl burnishing structure, and a cam actuated mechanism intermittently reciprocable and adapted to effect the discharge of the ultimate bowl from the machine.

3. In a machine for turning the bowls of tobacco pipes, a base, a rotary member supported on the base and provided with an annular series of spindles each adapted to have a previously bored corn-cob cylinder removably mounted thereon, motor driven means for rotating the spindles rapidly, motor driven means for rotating the spindle supporting member, a combined cutter and trimmer assembly independently driven and adapted to shape the exterior contour of the cob cylinders and simultaneously trim the ends thereof, a yieldable mounted pressure plate adapted to engage the unsupported end of the shaped cylinders as each of them passes from the cutter assembly, resiliently mounted burnishing apparatus adjustably positioned relative the rotating periphery of the shaped cob cylinder, means whereby the said spindle rotating means is maintained clear of each successive spindle after it passes beyond the burnishing apparatus, and an intermittently reciprocable, horizontally mounted pusher bar adapted to engage one end of a shaped and burnished cob cylinder to remove it from the spindle and discharge it from the machine.

4. In a machine for turning the bowls of tobacco pipes, a base, a rotary member supported on the

base and provided with an annular series of spindles each adapted to have a previously bored corn-cob cylinder removably mounted thereon, motor driven means for rotating the spindles rapidly, motor driven means for rotating the spindle supporting member, a combined cutter and trimmer assembly independently driven and adapted to shape the exterior contour of the cob cylinders and simultaneously trim the ends thereof, a yieldable mounted pressure plate adapted to engage the unsupported ends of the shaped cylinders as each of them passes from the cutter assembly, and means for burnishing the shaped cylinders comprising an arcuately formed plate pivotally mounted at one end to a similar member rigidly secured to the base, a pin and spring arrangement to resiliently support the free end of the first-named plate, a layer of leather co-extensive with said plate and whose upper surface is slightly concave suitably secured thereto, a layer of resilient material superimposed upon and co-extensive with the leather, and a layer of sandpaper superimposed upon the resilient layer, the sandpaper being provided with a series of longitudinal slits at spaced intervals throughout its length.

5. A pipe-bowl turning machine including a base and a horizontally disposed framework supported thereon, a primary motor and a rotary vertically disposed disc whose horizontal shaft is supported in bearings on the framework, speed reduction gearing for transmitting power from said motor to said disc, a circular series of spaced horizontally disposed spindles journaled in bearings near the periphery of the rotary disc, a sheave fixed to one extremity of each spindle, a belt continuously driven at a high rate of speed by said motor engageable with certain of said spindles but not engageable with all of them, a rotary cutter and cylindrical saw unit including a second motor to drive said cutter and saw at a high velocity, a yieldable pressure plate supported on a standard secured to said framework, an adjustable resiliently supported and hingedly mounted bowl burnishing structure, and means for effecting the discharge from the machine of the finished bowl, said means comprising a horizontally disposed bar slidably mounted in brackets secured to the base, an arcuately shaped pusher member rigid with an upward extension formed on one end of said bar, a roller journaled in the other end thereof, a compression spring surrounding the bar and interposed between one of said brackets and a pin carried by said arm, and a circular series of spaced cams formed on the face of one gear included in said speed reduction gearing to intermittently reciprocate the bar and thereby remove the finished bowl from each successive spindle passing the discharge point.

6. In a machine of the class described, in combination, a frame, a table supported for rotation vertically of said frame, a spaced annular series of work supporting spindles journaled in said table adjacent to the periphery thereof and on axes parallel with the axis of rotation of said table, means for rotating said table, independent means for rotating said spindles during a segment of the circle of travel of said table, a rotary cutter disposed for engagement with workpieces on said spindles while the spindles are being rotated, a yieldable mounted pressure plate mounted for contact by the free ends of workpieces as they leave the cutter, and a sanding device having a yieldable working surface disposed adjacent said table to burnish the work-

pieces successively as they are advanced from said cutter.

7. In a machine of the class described, in combination, a frame, a rotary table journaled in said frame, a spaced annular series of spindles positioned normal to the face of said table, a work supporting member carried by each of said spindles adapted to frictionally engage a hollow circular workpiece, means for driving said spindles during a predetermined arc of movement in each cycle of rotation of said table, a rotary cutter supported by said machine frame in cooperative relationship with the workpieces to form the periphery thereof successively, spaced circular saws associated with said cutter device to trim the ends of said circular workpieces successively, a yieldably mounted member for engaging the free ends of workpieces as they leave the cutter and saws, and a burnishing device for finishing said workpieces after they have been cut.

8. In a machine of the class described, in combination, a frame, a table supported for rotation vertically of said frame, a spaced annular series of work supporting spindles journaled in said table adjacent to the periphery thereof and on axes parallel with the axis of rotation of said table, means for rotating said table, independent means for rotating said spindles during a segment of the circle of travel of said table, a rotary cutter disposed for engagement with workpieces on

said spindles while the spindles are being rotated, a yieldably mounted pressure plate mounted for contact by the free ends of workpieces as they leave the cutter, a sanding device having a yieldable working surface disposed adjacent said table to burnish the workpieces successively as they are advanced from said cutter, and means for automatically ejecting workpieces after leaving said sanding device.
